UNITED STATES PATENT OFFICE.

OSCAR H. DESMARAIS, OF HACKENSACK, NEW JERSEY, ASSIGNOR OF ONE-HALF TO
CHARLES W. LOCKWOOD, OF NEW YORK, N. Y.

AWNING.

1,267,192.

Specification of Letters Patent. Patented May 21, 1918.

Application filed August 10, 1917. Serial No. 185,510.

To all whom it may concern:

Be it known that I, OSCAR H. DESMARAIS, a citizen of the United States, and a resident of Hackensack, county of Bergen, and State 5 of New Jersey, have invented a new and Improved Awning, of which the following is a full, clear, and exact description.

This invention relates to awnings adapted especially for windows, porches, doors or 10 the like, and has particular reference to means whereby the awning may be nested in close position at the top of the opening for which it is provided.

Among the objects therefore of this invention is to improve the construction of an awning so as to adapt it to be put up or taken down with facility.

Another object of the invention is to improve the construction of an awning whereby when in extended position for use it will be held in substantially rigid position to prevent rattling, flapping or the like.

A still further object is the provision of an awning which while it is retained securely at the top of a window (and by the term "window" as used hereinafter I mean to cover any analogous opening to be protected by an awning) the main portion thereof may be manipulated with facility so as 25 to collapse or fold into a very small compass within the top of the window just below the lintel, and from which folded position the awning may be as easily extended when desired.

With the foregoing and other objects in view the invention consists in the arrangement and combination of parts hereinafter described and claimed, and while the invention is not restricted to the exact details of 35 construction disclosed or suggested herein, still for the purpose of illustrating a practical embodiment thereof reference is had to the accompanying drawings, in which like reference characters designate the same parts 40 in the several views, and in which—

Figure 1 is an outside elevation of a window equipped with my improvement extended;

Fig. 2 is a vertical sectional view of the 50 same on the line 2—2 of Fig. 1;

Fig. 3 is a horizontal sectional detail on the line 3—3 of Fig. 2;

Fig. 4 is a similar view on the line 4—4 of Fig. 2;

Fig. 5 is a detail perspective view of the 55 inner end of one of the brace arms;

Fig. 6 is a horizontal sectional detail on the line 6—6 of Fig. 8;

Fig. 7 is an inside elevation with the parts 60 ready to be folded below the lintel;

Fig. 8 is a vertical sectional view on a plane corresponding to Fig. 2, but showing the folding in an intermediate stage; and

Fig. 9 is a view of the same with the folding 65 completed.

Referring now more specifically to the drawings, I indicate a window frame 10 having a lintel 11 along which are arranged a series of hooks 12, or their equivalent, to which the top 13 of the awning is adapted 70 to be connected by means of eyes 14 or the like, secured along its upper edge. The hardware accompanying the awning includes a pulley 15 secured at the center of the lintel. A pair of socket pieces 16 are 75 fixed to the sides of the window frame on opposite sides of the window and at about the level of the lower end of the awning when extended. The sockets 16 have vertical openings. At one side of the window 80 frame is secured another pulley 17, and preferably at the side of the window opposite the pulley 17 is arranged a cleat 18 for a purpose presently to appear. I would call attention in this connection also to a pair of 85 blocks 19 secured to opposite sides of the window frame a few inches below the lintel.

Adjacent to the top of the main portion 20 of the awning is a transverse bar 21 fixed in any suitable manner permanently in the 90 awning and having exposed ends having eyes through which bolts 22 project from the blocks 19. Winged nuts or the like 23 co-operate with said bolts to fasten the bar 21 rigidly in place in the window frame. This 95 attachment is permanent or is maintained so long as the awning is to be kept in connection with the window, and this connection is effected after the eyes 14 are engaged over the several hooks 12.

Just below the bar 21 is a rectangular frame 24 shown in section in Fig. 2 and in full in dotted lines in Figs. 1 and 7, and extending practically fully across the awn-

ing. This frame 24 defines what may be regarded as a panel portion of the awning substantially equal in extent to the space between the bar 21 and the window lintel. 5 A cord 25 is fixed at a point 26 on the inside of the awning at about the center of the lower edge of this frame, and it extends thence downward and outward and thence upward over the lower edge 27 of the awning, and finally inwardly and downwardly over the pulley 15 within reach of the operator.

10 Adjacent to the lower edge 27 of the awning is a transverse stiff plate 28 of metal or other suitable material extending substantially across the awning, and just above this plate and spaced somewhat therefrom is another bar 29. A cord 30 is connected at one end at a point 31 on the outside of the awning 15 at about the center of the bar 29, and this cord extends thence upwardly over a pulley 32 close to the pulley 15, and thence laterally over the side pulley 17.

15 At each side of the awning is arranged a triangular flap 33 attached permanently at its outer edge to the main portion of the awning 20. This flap is indicated as substantially of the form of a right-angle triangle whose hypotenuse is the edge of connection with the main awning. The right-angle corner portion of each flap is connected by means of a strap 34 of any suitable nature adjacent to the inner end of a brace arm 35 whose outer end is hinged at 36 to 20 the end of a rod 27 located within the lower edge 27 of the awning. At the inner end of each brace arm 35 is a downwardly projecting spur 37 adapted to fit downwardly into a socket member 16, while the extreme end 25 of the arm lies flat against the side of the window frame.

25 The foregoing description will be understood as applicable to the awning in its operative position. If, now, it is desired to fold or collapse the awning so as to nest just within the top of the window frame, the first operation is to disconnect the spurs 37 of the arms 35 from the sockets 16 and swing said arms toward each other and then outwardly into substantially the same plane against the inner side of the lower end of the awning, where they are held by a strap 35', as shown in Fig. 7. This movement of the arms will carry with it the two flaps 33 so that they will lie flat against the inner face of the awning. The next step is to grasp the free end of the cord 30 below the pulley 17, which draws upwardly on the awning from the point 31 and brings the awning into the position of Fig. 8. This cord 30 will then be held steady with one hand while the operator grasps the other cord 25 where it hangs within and below the pulley 15, which will act directly to fold 60 the two parts of the awning that are depend-

ing at this time and bringing the awning into the folded position shown in Fig. 9, and with the portion thereof in which the frame 24 is located flat against the outer side of the remainder of the awning and substantially parallel to that portion of the awning between the bar 21 and the top of the window. The plate 28 serves to hold the lower end portion of the awning flat, so that when the awning is finally folded it will occupy a minimum space laterally of the window. 75 After this position is reached the cord 25 will be snubbed upon the cleat 18, where it will remain until the awning is to be lowered again. Obviously the extension of the awning is effected by a reversal of the foregoing steps, except that the operator will have nothing to do with the cord 30, since it will take care of itself when the awning is moving downward. 80

85 I claim:

1. In an awning, the combination of a main awning panel, means to attach the upper edge thereof in fixed position, a bar extending across the awning panel just below the upper edge, means to secure the ends of the bar to a window frame, a stiff rectangular member carried by the awning below said bar and having a width substantially equal to the space between the bar and the top of the window, a cord serving to lift the lower portion of the awning to the top of the window, and another cord connected to the inner face of the awning at about the center of the lower portion of said stiff member and serving to fold the awning complete in a small rectangular body within the top of the window frame. 90

2. The combination of an awning, means to secure the upper portion of the awning to a window frame, two stiff rectangular members secured in the awning, one just below the attachment means and the other adjacent to the lower edge of the awning, a cord secured to the outer face of the awning 105 above the lower rigid member, whereby such portion of the awning is adapted to be lifted to the top of the window frame, and a second cord extending around the bottom of the awning where it is secured on the inner face of the awning adjacent to the other of said rigid members, and whereby the awning is given a final folding operation. 110

3. The combination of a main awning panel, means to secure the upper end of said panel to the upper portion of a window, a pair of triangular flaps each connected along one edge to an edge of the awning, a rod extending across the lower edge of the main awning panel, a pair of brace arms hinged 120 to the ends of said rod, means flexibly connecting the flaps to said arms, and means to anchor the inner ends of said arms to the sides of the window frame. 125

4. The herein-described awning structure 130

comprising, in combination, a pair of socket members for the opposite sides of a window and having vertical openings, a main awning panel, means to fix the upper end of said panel to the top of the window, a pair of brace arms fixed at their outer ends to the lower corners of the said panel, the inner ends of said arms having downwardly pro-

jecting spurs coöperating with said sockets, a pair of triangular flaps each connected 10 along one edge to a side edge of the main panel, and means to secure the flaps to said arms, said arms and flaps being foldable against the inner face of the main panel.

OSCAR H. DESMARAIS.
